UNITED STATES PATENT OFFICE.

ARTHUR THOMPSON, OF BROOKLINE, MASSACHUSETTS.

VACUUM-CLEANER.

1,180,679.

Specification of Letters Patent. Patented Apr. 25, 1916.

Application filed June 4, 1915. Serial No. 32,182.

To all whom it may concern:

Be it known that I, ARTHUR THOMPSON, of Brookline, in the county of Norfolk and State of Massachusetts, a citizen of the United States, have invented a new and useful Improvement in Vacuum-Cleaners, of which the following is a specification.

The purpose of my invention is to increase the usefulness of the cleaner by giving its nozzle a greater range of adjustment so that it may be readily and usefully used upon comparatively thin carpets and also upon carpets having a thick pile; also, to provide means whereby threads and other like matters may be dislodged from the floor so that they may be readily attracted by the air blast and drawn into the dirt receptacle.

The construction of my cleaner also provides a ready means for connecting the exhaust with a secondary nozzle of some character whereby the cleaner may be used upon furniture or other articles than the carpet or floor.

My invention will be understood by reference to the drawings in which it is shown in its preferred and simplest form.

Figure 1 is a side elevation of a cleaner embodying my invention, the nozzle, thread-lifting device and rod being shown in a section taken on line 1-1 of Fig. 4. Fig. 2 is a detail showing the height-adjusting mechanism in section on line 2-2 of Fig. 3. Fig. 3 is a view to illustrate particularly the under side of the nozzle, the thread-lifter being in place, and Fig. 4 is a longitudinal section of the nozzle showing the means of attachment of the thread-lifter in the nozzle.

A is a casing within which is located an electric motor by means of which the exhaust fan contained in so much of the casing as is marked A¹ is operated. A² shows the means whereby the electric conductor is connected to the motor, current being conducted to the motor from any convenient source such as an electric light bracket. B is the air conduit which extends from the fan contained within the portion of the casing marked A¹ to the nozzle C. These parts are all of ordinary construction and need not be further explained except that the conduit B has an opening b over which lies a pivoted cover B¹ which is adapted to be swung up out of the way to allow a hose coupling to be passed in through the opening b to the fan chamber within the casing A, thus cutting out the floor nozzle and causing the fan to draw through the coupling and hose. This is useful when it is desired to connect the fan chamber with any other form of nozzle than that shown. This construction allows the floor nozzle C to be made integral with the casing A, A¹.

A³ is a yoke piece attached to each side of the casing A, A¹, having pivotally mounted thereon a wheel A⁴. These parts being also common to the art are not shown in detail. They form a unitary structure which is mounted to swing with relation to the axis of the supporting wheels. For this purpose this structure has brackets C² integral with the nozzle C, and in these brackets is carried a rod C¹ on each end of which is mounted an arm D, D¹ and each one of these arms D, D¹ carries a stud upon which is mounted a wheel d to turn thereon so that the device as a whole is supported on the floor by the three wheels A⁴, d, d. The casing is thus mounted eccentric to the wheels d, the rod C¹, arms D, D¹ forming a wheel frame carrying the wheels d, d. The height of the nozzle C from the floor depends upon the angle of the arms D, D¹ with the floor. As shown in Fig. 2, the nozzle is quite close to the floor, but by turning and locking these arms so that they are more nearly horizontal than as shown in Fig. 2 it will be seen that the nozzle C will be lifted with relation to the axles of the wheels. To accomplish this lifting I have provided at one end of the device a handle d¹ which is attached to and forms part of the arm D, and fast upon the rod C¹ I have provided one member d² of a lock, the other member comprising a pin d³ sliding in a recess or passage in a portion of the casing A¹, this passage being lettered d⁴ and containing also a spring d⁵ the front end of which bears against said pin d³ and the rear end of which engages a shoulder d⁶ in the passage. The purpose of the spring d⁵ is to keep the pin d³ in its forward position. The lock member d² is segmental in character and is provided with recesses d⁷ adapted to receive and engage the end of the pin d³. This mechanism is such that upon moving the handle d¹ in either direction the arm D and rod C¹ to which it is pinned is turned either to depress or raise the arm D, and as the arm D¹ is pinned to the rod C¹ parallel with the arm D the turning of the rod C¹ raises or lowers the arm D¹ at the further end of the machine as well, and as these two arms carry the

wheels d , the position of the rod C^1 and nozzle C with relation to the axles of the wheels is thus changed and the nozzle C raised or lowered.

- 5 Within the nozzle C is located a thread-lifter E . This thread-lifter comprises preferably a wooden bar to the under surface of which felt or other textile material is applied. In practice I prefer to use a series of pieces of felt e or the like preferably set at an angle as shown so that alternate pieces will be parallel with each other. For best results these pieces of felt project slightly beyond the plane of the lower face 10 of the nozzle, and the thread-lifter E is yieldingly supported in the nozzle, the felt pieces e as the nozzle is moved over the carpet, engaging the threads and the like to loosen them from the carpet so that they are lifted by the exhaust and drawn up into and through the nozzle. They with the dust, etc., passing through the fan, are carried into the pipe F to the end F^1 of which the usual dust bag (not shown) is attached.
- 15 25 I prefer to support the thread lifter in the nozzle in the following manner: The thread-lifter is provided with openings e^1 at each end, these openings being located with reference to the screw pins e^2 so that the pins serve as guides to the vertical movement of the thread-lifter. Spring catches e^3 are attached to the interior of the nozzle. These spring catches are in the nature of loops having a contracted opening as at e^4 20 and the thread-lifter E has at each end a link e^5 made of wire or the like which, when the lifter is pushed into place, snaps by the portion e^4 of the spring catch so that the lifter E hangs normally upon this portion e^4 .

30 35 40 In order to keep the thread-lifter in proper relation to the opening in the nozzle, I provide leaf springs e^6 attached at one end to the thread-lifter, the free ends of these springs bearing against the shoulder e^7 within the nozzle. Thus the lifter may be easily withdrawn from the nozzle if it is not desired to use it, and may be as easily replaced and when replaced will serve its purpose projecting preferably slightly beyond the opening to the nozzle so that it will engage the surface of the carpet.

45 50 55 To operate this cleaner I have provided a bail G of ordinary form which is mounted to swing on the rod C^1 , one arm of the bail being at each end of the rod C^1 , and in addition I may provide means for adjusting the angle of the handle with relation to the floor, such as a segment G^1 attached to one of the brackets C^2 and a slotted, threaded pin g , the slot in which fits over the segment G^1 (see Fig. 2), the outer end of the pin g carrying a thumb nut, the whole forming a

clamp by which the pin and the segment may be bound together. The end of the bail G carries a socket piece G^2 to receive the end of a handle, a set screw G^3 being provided to hold the handle in place. This matter I have not illustrated fully, nor is it necessary to describe it further as it is common in all machines of this class.

I do not mean to limit myself to the precise construction shown as other means of adjusting and locking the height of the nozzle from the floor may be adopted which will be within the scope of my invention. Moreover, the thread-lifter may be otherwise constructed and supported and yet be within the scope of my invention.

What I claim as my invention is:—

1. In a device of the kind described, a casing comprising nozzle, a motor and a fan located in said casing, and a support for said casing comprising wheels, adjustable means for mounting said casing on said wheels whereby the relation of the nozzle to the wheels may be adjusted, said means comprising a wheel frame, a pivotal connection between said wheel frame and said casing and wheels mounted on said wheel frame eccentric to said pivotal connection, in combination with a lock adapted to lock said casing and said wheel frame, one member of said lock comprising a segment mounted on said wheel frame and the other member a spring-controlled pin mounted on said casing and located to engage said segment.

2. In a device of the kind described, a casing comprising nozzle, a motor and a fan located in said casing, and a support for said casing comprising wheels and adjustable means for mounting said casing on said wheels whereby the relation of the nozzle to the wheels may be adjusted, said means comprising a rod mounted to turn with relation to said casing, arms located at each end of said rod, a wheel mounted in each arm eccentric to said rod, a segment mounted on said rod in proximity to said casing, a spring-controlled pin mounted in said casing to engage said segment and a handle mounted on said rod whereby said segment may be operated to adjust the relation of said wheels to said casing.

3. In a device of the kind described, in combination with a nozzle and adjustable means for regulating the height of said nozzle above the work, thread-picking means mounted in said nozzle; and means whereby said thread-picking means will automatically adjust itself with respect to the work co-operatively with the position of said nozzle
